 American Can Company, New York, N. Y., a
 corporation of New Jersey

Application June 19, 1944, Serial No. 540,927

10 Claims. (Cl. 91—45)

1

This invention relates to a machine for spraying surfaces of articles with a coating material and has particular reference to varying the quantity of coating material in the spray in accordance with a variation in the distance between the point of discharge and the surface being sprayed to provide an even coating of the material on such surface.

In the spray coating of articles, the spray gun used and the article being sprayed usually are moved relative to each other. When spray coating irregular shaped articles according to usual methods, portions of the article which are spaced farther away from the spray gun receive a thinner coating of the sprayed material than do portions closer to the gun. This results in uneven coating which in most instances is undesirable.

The present invention contemplates overcoming such difficulties by regulating the discharge from the gun in direct proportion to the distance of the sprayed surface from the point of discharge to control the quantity of coating material sprayed upon the surface.

An object of the invention is the provision of a machine for spraying surfaces with a coating material wherein the quantity of coating material discharged from the spraying devices for application onto the surfaces is controlled in accordance with the distance between the surface being sprayed and the spraying devices so that a film of coating material of uniform thickness will be applied to all surfaces being sprayed.

Another object is the provision in such a machine of devices for effecting relative movement between an irregular shaped article to be sprayed and a spray gun having an orifice controlled by a needle valve wherein the needle valve is operated in time with the movement and in accordance with the distance between the gun and the varying surfaces of the article to insure the application to the surfaces of a film of coating material of uniform thickness.

Another object is the provision in a machine of this character of a valve controlled spray gun which is rotatable and insertable into an article of irregular contour while the article is held stationary for spraying the inside surface of the article while varying the quantity of coating material discharged from the gun in accordance with the contour of the article so that a film of coating material of uniform thickness may be applied to the surfaces.

Another object is the provision in such a machine of control devices for the valve in the spray gun wherein quick opening, sensitive regulation,

2

and sharp cut-off of the valve may be had while the gun is rotating.

Numerous other objects and advantages of the invention will be apparent as it is better understood from the following description, which, taken in connection with the accompanying drawings, discloses a preferred embodiment thereof.

Referring to the drawings:

Figure 1 is a longitudinal sectional view of principal parts of a spraying machine embodying the present invention with parts broken away and showing a spray gun in position prior to insertion into a can body;

Fig. 2 is a rear elevation of the machine shown in Fig. 1, with parts broken away;

Fig. 3 is an enlarged view similar to Fig. 1 showing the spray gun in spraying position within the can body;

Figs. 4 and 5 are transverse sectional views taken substantially along the lines 4—4 and 5—5 in Fig. 1;

Fig. 6 is a perspective detail of parts shown in Fig. 3;

Figs. 7 and 8 are transverse sectional views taken substantially along the lines 7—7, 8—8 in Fig. 3; and

Fig. 9 is an end view of a rectangular can body indicating diagrammatically several positions of the spray projected against the inside surface of the body as an incident to spray coating such a surface.

As a preferred embodiment of the instant invention the drawings illustrate a machine for spraying a uniform film of coating material onto the inside surfaces of oblong rectangular sheet metal can bodies. However, the invention is equally well adapted to spraying outer as well as other inner surfaces and to other articles having curved, irregular, or plane surfaces and a more or a less elaborate machine can be used while fulfilling the same principles of invention.

In the instant machine the can bodies, indicated by the letter A, are carried in a horizontal position through a vertically disposed circular path of travel which extends through a spraying station X (Figs. 1 and 2). The bodies are advanced in an intermittent or step-by-step manner and come to rest individually at the spraying station for the spraying operation. While at the spraying station, a continuously rotating horizontally disposed spray gun B then in line with the middle of the can body at rest in the station, moves into and out of the body and sprays its interior walls. Such a gun has a discharge nozzle arranged to direct a single spray against a side

wall of the body. During this spraying operation the quantity of coating material discharged from the nozzle is controlled in accordance with the distance between the nozzle and the wall being sprayed. It is this controlled operation of the spray that results in the uniform application of the coating material.

In the instant case where the can body has an oblong rectangular cross section, as best shown in Fig. 9, the distance between the parts of the surface being sprayed and the nozzle varies as the spray gun rotates within the body. The farther away the surface is from the nozzle, the greater will be the area of wall space covered by the spray from the nozzle and accordingly the less dense the spray will be. The diagrammatic showing of different locations of the spray stream in Fig. 9 graphically indicates this. With a constant spray as used in conventional practices, a thinner film of coating material will be applied to the more distant surface parts of the body since the spray stream is spread out over a greater surface.

In the instant invention this variation in distance is utilized for controlling the nozzle discharge so that an increased quantity of coating material will be ejected from the nozzle as the distance between the nozzle and the area sprayed increases. In this manner a uniform film of even thickness of the coating material is applied to the body surface regardless of the contour of the body being sprayed.

Reference will now be had to a more detailed description of the machine and its operation. Movement of the can bodies A through a circular path of travel toward and away from the spraying station is effected by a rotatable carrier turret 21 (Figs. 1, 3 and 7) having a plurality of pockets 22 which are spaced around the periphery of the turret and in which the can bodies are carried. The bodies are deposited in the turret pockets and are ejected therefrom in any suitable manner.

The carrier turret 21 is mounted on the outer end of a horizontal turret shaft 23 (see also Fig. 2) which is carried in a pair of spaced bearings 24, 25 formed in brackets 26 which extend up from opposite ends of a frame 27. This latter constitutes the main frame of the machine.

The turret shaft 23 and the turret 21 carried thereon are intermittently rotated by a conventional indexing device located at the end of the machine opposite the turret. The indexing device includes a Geneva wheel 28 (see also Fig. 5) and a cooperating Geneva actuating arm 29. The Geneva wheel is mounted on the turret shaft 23. The Geneva arm 29 is secured to one end of a drive shaft 31 journaled in spaced bearings 32, 33 (Fig. 1) formed in the main frame of the machine. The drive shaft may be driven from an outside source of power in any suitable manner, as for example through a gear 34 mounted on the outer end of the shaft.

The spray gun B at the spraying station X of the machine is disposed in a horizontal position in line with the middle of a can body brought to rest at this station by the turret 21. The gun at all times is parallel to the turret shaft 23. The gun in general is cylindrical in shape and is mounted for rotation in a pair of longitudinally spaced split bearings 41, 42 formed in a horizontal slide bracket 45 (Figs. 1, 3 and 4). The slide bracket is formed with slide tongues 46 (see also Fig. 5) which operate in longitudinal slideways 47 in the main frame 27.

Rotation of the spray gun B is brought about by a spur gear 51 (Figs. 1 and 3) which surrounds the gun and which is keyed in place on the gun. This gear meshes with and is driven by a gear 52 which is formed integrally with a wide driving gear 53 constituting a composite gear unit. This composite gear unit is mounted loosely on the turret shaft 23 between a pair of retaining bearings 55, 56 formed on the slide bracket 45. The retaining bearings provide support for the turret shaft intermediate its main bearings 24, 25 and also retain the composite gear unit in place within the slide when the latter moves, as will be hereinafter explained. The composite gear unit is continuously rotated by a main driving gear 57 carried on the inner end of the drive shaft 31.

The spray gun B is shifted into and out of the can body A for the spraying operation by movement of the slide bracket 45 along its slideways 47 while the body is at rest at the spraying station. This movement of the slide bracket is brought about by cam action. For this purpose the slide bracket carries a cam roller 61 which operates in a cam groove 62 formed in a barrel cam 63 mounted on and continuously rotated by the drive shaft 31. The cam shifts the slide bracket and the spray gun carried thereon when the carrier turret 21 is at rest.

Referring now to the details of the spray gun itself it will be observed that it is made up primarily of an outer cylindrical shell 65 (Figs. 3 and 7) and an inner tube member 66 concentrically disposed within the shell and in spaced relation. This construction sets off an annular air passageway 67 therebetween. The outer ends of the shell and the tube member, i. e., the end adjacent the turret 21, are secured in a nozzle head 68. The nozzle head is formed with a tapered valve seat embodied in a needle valve 71 which is located at the horizontal center of the tube member 66.

Head 68 is formed with an L-shaped channel 72 adjacent to and on one side of the valve seat. The horizontal leg of the channel communicates with the annular air passageway 67 while the vertical leg of the channel terminates adjacent the outer end of the tapered valve seat and is disposed at right angles to the valve thus providing a single outlet. The inner or opposite end of the shell 65 carries a stuffing box nut 75 which surrounds the tube member 66 and which holds a tapered sealing gasket 76 in place between the shell and the tube member. This seals the inner end of the passageway 67.

Compressed air is introduced into the air passageway 67 by way of a pipe 81 which leads from any suitable source of compressed air. The gun end of the pipe is threaded connected into the upper half of the split bearing 42 and communicates with a recess 82 formed in the bearing. A port 83 in the gun shell 65 constitutes a connection from the bearing recess to the air passageway 67 and directs flow of air from the recess into the passageway as the gun rotates.

A flexible ring stuffing box device 84 is located in the bearing recess 82 and surrounds the outer shell 65 of the gun. This prevents leakage of air past the bearing. The stuffing box device is held in place by a collar nut 85 threadedly engaged in one end of the bearing 42.

Compressed air introduced into the circular air passageway 67 flows along the length of the gun and into the L-shaped channel 72 in the nozzle head 68. The air continually discharges from the outlet end of the channel in a single jet issuing

at an angle that is normal to the axis of the gun. Thus it is directed against the interior surfaces of the can body while the gun with its nozzle head is rotating inside the can body.

The coating material to be sprayed onto the can body walls is conveyed through the inner tube member 66 and is discharged by way of the needle valve 71 in the nozzle head 68. For this purpose the inner end of the tube member extends inwardly beyond the outer shell 65 of the gun and terminates in a recess 91 (Fig. 3) formed in a stationary block 92 held in place by a clamp ring 93 threaded onto the collar nut 85 of the gun bearing 42. The block 92 and the collar nut are formed with suitable cooperating stuffing box members which surround the extended end of the tube member 66 and thus prevent leakage of coating material past this joint as the gun rotates.

The coating material is introduced into the block recess 91 and from there into the tube member 66 by way of a supply pipe 94. The machine end of the pipe is threaded into the block 92 and is in communication with the recess 91. This pipe provides a lead from a suitable source of supply of the coating material. The coating material preferably is maintained under a pressure sufficient to force it into and through the inner tube member of the gun.

The needle valve 71 of the gun which is in communication with the interior of the tube member 66 is normally closed to prevent spraying of the coating material. It is first opened for spraying when the nozzle head 68 comes into spraying position within the can body. In the closed position of the valve, a tapered valve face 96 fits tightly against the valve seat. Valve face 96 is formed on the outer end of a long valve rod 97 (Fig. 3) which extends back through the interior of the tube member 66 along its longitudinal center and through the recess 91 in the block 92.

The valve face 96 and its rod 97 rotate with the spray gun. That portion of the rod which is within the recess 91 of the block 92 is formed with a double flattened feather section 98. The feather section has longitudinal movement within a pair of diametrically opposed feather slots 99 formed in the inner end of the tube member. With such a tongue and slot connection the valve rod may be shifted longitudinally of the tube member to open and close the valve while the gun is rotating.

Beyond the recess 91 in the block 92 the valve rod 97 merges into an enlarged actuating stem 101 which projects beyond the stationary block to provide for actuating the rod, as will be hereinafter explained. Leakage of coating material around the stem is prevented by a stuffing box cap 102 which surrounds the stem and which has a part threaded onto a hub section 103 of the block.

The shifting of the valve rod 97 to open and close the discharge valve 71 is effected in time with the movement of the gun slide bracket 45 and the spray gun B carried thereon. This is brought about by an actuating sleeve 111 (Figs. 1, 3 and 8) which surrounds and has a yieldable connection with the outer end of the valve stem 101. The sleeve 111 is mounted for sliding movement in a horizontal position within a bearing 112 formed on the slide bracket 45. Such movement takes place through a valve opening stroke and thence through a valve closing stroke in time with the movement of the slide bracket 45.

Where it extends into the sleeve 111, the valve stem 101 is formed with a flange 115 (Figs. 3

and 6). The inner face of the stem flange is formed with a pair of diametrically opposed lugs 116 which engage within slots 117 formed in a rotatable disc 118 also disposed in the sleeve. The disc is formed with a centrally located boss 119 which engages and rotates against a stationary stop plate 121. The boss is relatively small in area to reduce frictional engagement with the non-rotatable plate.

Stop plate 121 is held against movement by a pin 124 which extends transversely through the plate, as best shown in Fig. 8. The ends of the pin extend through elongated slots 125 (see also Fig. 1) cut in opposite sides of the sleeve and are secured in the bearing 112. Functionally, therefore, the stop plate is a part of the slide bracket 45 but permits free horizontal movement of the sleeve within the bearing 112.

A compression spring 131 housed within a bore 132 formed in the valve stem 101 (Fig. 3) provides a cushion between the stem and the disc 118. It also presses the disc against the stop plate 121 and when unrestricted forces the valve face 96, on the end of the valve rod 97, against the valve seat thus closing the discharge valve 71. This is the normal position of the valve.

The flange 115 of the valve stem 101 is formed with a cam surface 135 (see also Fig. 6). A cam roller 136 (Fig. 3) is located within the sleeve 111. The cam roller is mounted on the inner end of a pin 137 which is secured in a stop boss 138 formed on the exterior of the sleeve.

The sleeve 111 is shifted through a valve opening stroke, toward the right as viewed in Figs. 1 and 3, when the spray gun enters a can body at rest in its spraying position. An adjustable stop screw 141 is threaded into the sleeve bearing 112. The inner end of this screw projects into a clearance recess 142 formed in the inner end of the bearing 112. The stop boss 138 strikes against the end of the screw when the sleeve is shifted for its valve opening. By adjustment of this screw the maximum size of the discharge nozzle opening is determined and hence the amount of coating material issuing from the nozzle when it is initially opened, may be regulated.

The movement of the valve actuating sleeve 111 is brought about by cam action and through a yieldable connection which includes a plunger 145 (Fig. 3). The plunger is disposed within the outer end of the sleeve adjacent the outer face of the stop plate 121. A compression spring 146 is interposed between the plunger and the outer end of the sleeve. The terminal end of the sleeve is partially closed by an inwardly bent stop collar flange 147. This retains the spring in position within the sleeve.

The plunger 145 is mounted on an eye bolt 151 which extends through the flange opening and is connected pivotally to a vertical leg 152 of a bell crank 153 (see also Figs. 2 and 4). This bell crank is mounted on a pivot stud 154 carried in a lug 155 which projects out from the slide bracket 45. The bell crank thus bodily moves with the slide bracket. A second leg 156 of the bell crank carries an actuating roller 157 which engages against a foot 158. The roller rides along the foot as the slide bracket 45 reciprocates.

The foot 158 is at all times parallel with the path of travel of the slide bracket 45 and is formed on the outer end of an arm 162 (Figs. 2 and 4). The arm is mounted on and keyed to a pivot shaft 163 carried in bearings 164 formed in the machine main frame 27. The shaft also carries a cam lever 165 having a cam roller 166 which operates

in a cam groove 167 of a face cam 168 formed in the outer end of the slide bracket barrel cam 63. The timing of the face cam 168 is thus tied-in with the rotation of the barrel cam 63 and with the reciprocation of the slide bracket 45.

Hence on a forward stroke of the slide bracket 45 to insert the spray gun B into the can body A to be sprayed, the face cam 168 rocks the cam lever 165 and the arm 162 and thus lifts the foot 158 formed thereon. These parts remain in this position during the entire spraying operation. This lifting of the foot through the actuating roller 157 thus rocks the bell crank 153 in a clockwise direction (Fig. 3). This movement of the bell crank draws the plunger 145 outwardly and shifts the valve actuating sleeve 111 outwardly through the yielding action of the spring 146.

The yielding action of the compression spring 146 compensates for any overthrow of the face cam 168 and permits full operation of the cam 168 even after the movement of the sleeve in its bearing 112 is arrested by the stop screw 141. This yielding feature permits of accurate adjustment for the amount of initial opening of the needle valve 71 by utilizing the stop screw to regulate the travel of the sleeve.

The sleeve movement affects the movement of the valve rod 97 to open the valve by the cam roller 136 moving with the sleeve. This roller presses against the valve control cam surface 135 on the rotating flange 115 of the valve stem 101. Movement is toward the right as in Fig. 3. Spring 131 is compressed and the rotating disc 118 is pressed tightly against the stationary stop plate 121. The longitudinal movement imparted to the valve rod 97 withdraws the valve face 96 from its seat and thus opens the discharge valve 71. The coating material under pressure within the tube member 66 thus discharges from the valve.

The air issuing from the outlet end of the channel 72 adjacent the valve 71 blows the discharging coating material into a spray of finely divided particles and projects it at right angles to the nozzle and against the inside surface of the can body A. This spray continues while the gun moves forward (toward the left as in Fig. 3) into and through the body and also while the gun moves back in a return stroke. Thus the entire inner surface is covered with a film of the coating material.

As the nozzle leaves the edge of the sprayed can body, on the return stroke of the gun, the valve 71 is immediately closed to prevent waste of coating material. This is brought about by a reverse shifting of the actuating sleeve 111 which now moves toward the left, as viewed in Fig. 3. This is brought about by lowering of the foot 158 which first relieves the pressure on the spring 146 whereupon the sleeve 111 is free to move. The spring 131 now becomes the prime mover and forces the valve rod 97 forward (left) first reseating the valve face 96. This closes the valve.

The description of the opening and closing of the discharge valve 71 up to the present time has not included the further control of the discharge valve 71 to insure the discharge of the coating material in carefully measured amounts in accordance with the distance intervening between the nozzle head 68 and the wall of the can body being sprayed. This additional partial opening and closing of the discharge valve is brought about by cam surface 135 on the rotating flange 115 of the valve rod stem 101 operating over the roller 136 then rotating on a stationary axis. 75

This cam surface is shaped in accordance with the contour of the can body being sprayed, i. e., in accordance with the distance the spray stream must travel at any moment during the gun's rotation.

Since the control cam is formed as a part of the valve rod and rotates with the spray gun it is always in time with the single jet of spray issuing from the gun nozzle and this insures accurate registration of the parts involved in spraying the irregular surface of the body. It is this control cam that insures the application to the inner surface of the can body, of a film of coating material having a uniform thickness extending over the entire surface sprayed, as hereinbefore explained.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a machine for spraying a coating material on a surface, the combination of an elongated spray gun having a discharge orifice, said gun being rotatable on its longitudinal axis, the surface sprayed being stationary and said gun having longitudinal movement relative to said surface at different distances throughout a spraying operation, a valve rod located in said gun for controlling the effective size of said orifice, means mounted adjacent said gun for moving said valve rod in opposite directions respectively to open and close said orifice, and means operating adjacent said gun in accordance with the relative distances between the gun and the surface being sprayed for altering the position of said valve rod when said orifice is open to vary the size of said orifice and thus control the quantity of coating material passing through said orifice to insure a coating of even thickness on the said surface.

2. In a machine for spraying a coating material on the surface of an irregular shaped tubular article, the combination of an elongated spray gun having a discharge orifice, said gun being rotatable on its longitudinal axis, the tubular article being stationary while being sprayed and said gun being longitudinally movable relative to said article being sprayed at different distances from the gun, a valve rod located in said gun for controlling the effective size of said orifice, means mounted adjacent said gun for moving said valve rod in opposite directions respectively to open and close said orifice, and devices disposed adjacent said gun and having a shape corresponding to the contour of the article surface being sprayed and operating in accordance with the relative distances between the gun and the surface being sprayed for altering the position of said valve rod when the orifice is open to control the quantity of coating material passing therethrough to insure a coating of uniform thickness on the said article.

3. In a machine for spraying a coating material on the interior surface of an irregular shaped tubular can body, the combination of an elongated spray gun having an orifice for discharging a coating material and an air orifice for ejecting a blast of air at an angle to said discharge orifice for spraying the discharged coating material laterally of said gun onto said can body while the

latter is stationary, said gun being movable into said can body and having rotation on its longitudinal axis throughout a spraying operation, a valve rod located in said gun for controlling the effective size of said orifice, means mounted adjacent said gun for moving said valve rod to open and close said orifice, and devices connecting with said valve rod and rotatable with said gun and operating in accordance with the distance between the gun and that portion of the surface of the can body being sprayed for altering the size of said orifice to control the quantity of coating material discharging therefrom, whereby a uniform thickness of coating material is applied to the interior surface of the can body irrespective of the varying distances of the sprayed surfaces of the can body from said spray gun orifice.

4. In a machine for spraying a coating material on the interior surface of an irregular shaped tubular can body, the combination of an elongated spray gun having a discharge orifice, said gun being rotatable on its longitudinal axis and having longitudinal movement into and out of the can body while the latter is held stationary for a spraying operation, a valve rod located in said gun for controlling discharge of coating material from said orifice, means disposed adjacent said gun for closing said valve rod against said orifice, a cam located adjacent said gun and rotatable therewith, said cam having a surface contour which is variable in accordance with the relative distances between the said orifice and the can body surface for preventing the operation of said valve closing means and for changing the position of said valve rod to vary the quantity of coating material discharging from said orifice so as to provide an even thickness of coating on said can body surface, and means for rendering said cam ineffective when said valve closing means becomes effective.

5. In a machine for spraying a coating material on the interior surface of an irregular shaped tubular can body, the combination of an indexing turret for advancing a can body through the machine and for holding the body in a stationary position during a spraying operation, a slide having reciprocal movement adjacent said turret, a rotatable spray gun carried on said slide and having a discharge orifice, said gun being movable by said slide longitudinally of said held can body for spraying the interior surface thereof, a valve rod located in said gun for controlling the effective size of said orifice, means mounted on said slide for moving said valve rod to open and close said orifice, and devices carried by said slide and having independent movement thereon in accordance with the distance between the gun and that portion of the interior surface of the held can body being sprayed for further moving said valve rod after the orifice has been opened for altering the size of said orifice to control the quantity of spraying material discharging therefrom to provide an even thickness coating on the interior surface of the can body.

6. In a machine for spraying a coating material on the interior surface of an irregular shaped tubular can body, the combination of a support for holding a can body stationary during a spraying operation, a slide having reciprocal movement adjacent said support, a sleeve carried on said slide and movable thereon, a rotatable spray gun carried on said slide and having a discharge orifice, said gun being movable by the slide longitudinally into the held can body for spraying the

interior surface thereof, a valve rod located in said gun for controlling the effective size of said orifice, means for shifting the sleeve independently of the slide to move said valve rod to open and close said orifice, and devices carried by said sleeve and operable in accordance with the distance between the gun and that portion of the interior surface of the stationary can body being sprayed for shifting the valve rod after the orifice is open for altering the size of said orifice to control the quantity of spraying material discharging therefrom to provide an even thickness coating on the interior surface of the can body.

7. In a machine for spraying a coating material on the interior surface of an irregular shaped tubular can body, the combination of an intermittently rotatable support for holding a can body stationary during a spraying operation, an elongated rotatable spray gun having a discharge orifice and being movable longitudinally of its axis into the stationary can body for spraying the interior surface thereof, an elongated valve rod located in said gun and rotatable therewith on their longitudinal axes and for controlling the effective size of said orifice, a spring carried by said valve rod for moving the same to close said orifice, and a cam carried by said valve rod and rotatable therewith said cam having a surface of irregular contour for variably overcoming the action of said spring to alter the size of said orifice and thus regulate the quantity of spraying material discharging therefrom, the irregular contour of said cam surface constituting an increment of the distance between the gun and that portion of the interior surface of the can body being sprayed to provide an even thickness coating for the interior surface of the can body.

8. In a machine for spraying a coating material on the interior surface of an irregular shaped can body, the combination of an intermittently rotatable support for said can body, an elongated spray gun having a discharge orifice for spraying the interior surface of a can body while temporarily held stationary on said support, means for rotating said spray gun on its longitudinal axis, means connected with said rotating means for longitudinally reciprocating said gun into and out of said stationary can body during the spraying operation, a valve rod carried by and operated in said gun for controlling the effective size of said orifice, and devices actuated by said rotating means for longitudinally moving the valve rod to alter the size of said orifice and thereby vary the quantity of spraying material discharging therefrom to apply an even thickness coating to the interior surface of the can body, said variation of spraying material being dependent upon the distance between the gun and that portion of the interior surface of the can body being sprayed.

60 9. In a machine for spraying a coating material on the interior surface of an irregular shaped can body, the combination of a turret for presenting can bodies for a spraying operation, a spray gun having a discharge orifice, a valve rod carried by and operated in said gun for controlling the effective size of said orifice, means for moving said turret intermittently and for holding a can body stationary, means for reciprocating said spray gun to move its discharge orifice into said stationary can for spraying, means for continuously rotating said spray gun to pass said discharge orifice along the interior surface of the irregular shaped can body, and devices for actuating the said valve rod in accordance with the distance between the gun and that portion of the interior surface of

11

the can body being sprayed to regulate the quantity of spraying material discharged from said orifice to insure an even thickness coating on the interior surface of the can body.

10. In a machine for spraying a coating material on the interior surface of an irregular shaped tubular can body, the combination of an intermittently rotatable turret for successively presenting can bodies for a spraying operation, a rotatable spray gun having a discharge nozzle, said gun being movable longitudinally into a stationary can body for spraying the interior surface thereof, means for intermittently rotating said turret for temporarily holding stationary a can

12

body to be sprayed, a valve rod movable within said gun for controlling discharge of coating material from said orifice, a cam located adjacent said gun and having rotation therewith, said cam having a cam surface constituting an increment of the shape of said can body, a sleeve movable with and relative to said gun and enclosing said cam, an adjustable stop for limiting said sleeve movement, and means carried by said sleeve for engaging said cam surface to alter the position of said valve rod to vary the quantity of coating material discharging therefrom, whereby an even thickness coating is applied to the said surface.

HORACE J. PAYNTER.
